CLAIM

The ornamental design for a cart for storing dishes or the like, as shown and described.

DESCRIPTION

FIG. 1 is a perspective view of a cart for storing dishes or the like showing our new design;

FIG. 2 is a front elevation thereof; all other side elevations being identical thereto;

FIG. 3 is a top plan view thereof;

FIG. 4 is a bottom plan view thereof.
The broken line showing of wheels is for illustrative purpose and forms no part of the claim.
